MAGNETRON OSCILLATOR

Ernest G. Linder, Philadelphia, Pa., assignor to
 Radio Corporation of America, a corporation of
 Delaware

Application April 29, 1938, Serial No. 204,955

5 Claims. (Cl. 250—36)

My invention relates to ultra high frequency oscillation generators, and more particularly to an effective multiple-anode magnetron of improved design in which the anodes are an inherent part of a concentric line.

The increased efficiency at high frequencies of the four-anode magnetron, for example, as compared to the single or two-anode types is well established. It has been found that, as the frequency of operation of a four-plate magnetron is increased, certain difficulties arise which more than offset the advantage of the four anodes. In fact, it has been found that at very high frequencies such magnetrons may become inoperative. The difficulty referred to usually lies in the fact that the interelectrode leads, which are commonly employed to connect opposite anodes, become resonant, or at least have appreciable inductance, and so destroy the oscillator efficiency.

It is therefore an object of my invention to provide means for increasing the efficiency of an ultra high frequency magnetron oscillator.

A further object of my invention is to provide means whereby a multiple-anode magnetron oscillator may be made more efficient.

It is a further object of my invention to provide means in a magnetron oscillator for combining the features of resonant electrode oscillators and four-anode oscillators in a unique manner which overcomes the difficulties encountered in interconnecting the anode sections.

This invention will be better understood from the following description when considered in connection with the accompanying drawing. Its scope is indicated by the appended claims.

Referring to the drawing,

Figure 1 is an example of the conventional type of four-anode magnetron;

Figure 2 is a view, in perspective, of the construction of the cathode and anode elements of a magnetron according to this invention; and

Figure 3 is a connection diagram, partly in section, showing the circuit of a magnetron oscillator built according to this invention.

Referring now to Fig. 1, a four-anode magnetron is shown connected in the well known manner to an oscillatory circuit 3. An example of a magnetron of this type is found in a U. S. patent to Posthumus, No. 2,103,638, issued December 28, 1937, and assigned to the assignee of this invention. It is to be noted that opposite anodes are connected together by conductors 5 and 7, which extend around the outside of the plates. In practice, the actual connectors are placed substantially as indicated in this dia-

gram. The only practical way to reduce the length of the connectors is to reduce the overall diameter of the four anodes, because leads cannot be extended directly through the center of the tube without seriously affecting the performance of the oscillator. As the size of the anode electrodes is reduced, the ability to dissipate heat is also reduced, and therefore a practical limit is placed on such a change.

Referring to Fig. 2, a construction is shown which overcomes the difficulty of the connector lead inductance and permits the design of a tube which will handle large power without heating at frequencies higher than before obtainable. The anode electrode system comprises an outer metallic cylinder 9 and an inner metallic cylinder 11. The two cylinders are separated by a distance which is small in comparison to their diameters. The inner cylinder is axially divided into a number of arcuate sections so that the remaining surfaces are substantially equal to the spaces between them. For example, to obtain a four-anode magnetron a portion of the inner cylinder is bifurcated; that is, two opposite quadrants of one end of the inner cylinder are removed so that the end consists of two oppositely positioned arcuate surfaces 13 and 15, which are a continuation of the inner cylindrical member 11, each subtending an angle of substantially 90°.

The complete oscillator is shown in Fig. 3. The overall length of the inner and outer cylinders is such that they form a concentric resonant line which is approximately a half wave length long. A voltage node will exist at the mid-point of these electrodes, and therefore they may be conveniently positioned with respect to each other by means of a metallic annular collar 17. This collar is the only contact between the two electrodes and is utilized to apply the D. C. voltage from a battery 31 to the electrodes. One or more annular ceramic insulators 18 are placed within the inner cylinder to locate the cathode support member 20.

The outer cylinder 9 constitutes the envelope of the tube. Its two ends are sealed with glass end bells 19, 19' through the former of which extends the coaxial cathode support member 20. The cathode 35 is a continuation of this support, and has its active portion only in the region limited by the bifurcated section of the inner cylinder 11. The axial length of the bifurcated section is largely determined by the heat dissipation requirement.

A small conductive spring 21 is used to maintain a uniform tension on the cathode as the

tube expands. It is sealed in the glass end bell 18' at the cathode end of the tube, and provides one connection to the cathode. The cathode is heated by a battery 23, one end of which is 5 grounded. A resistor 25 is provided with which to adjust the cathode current. A radio frequency choke 39 is connected between this resistor and the cathode support 20. A second radio frequency choke 40 is connected between 10 the conductive spring 21 and ground. A magnetic field is provided by a coil 27 and an energizing battery 29. The coil is placed around the electrodes 13 and 15 in the manner shown.

Certain of the electrons attain a component 15 of motion along the cathode axis, and therefore tend to travel out of the magnetic field. When this occurs they quickly lose their spiral motion and pass to the positive anode. It is desirable to regulate this action to prevent excessive anode 20 current and to provide for optimum operating conditions. One effective remedy is to extend the region of magnetic field axially along the cathode. Another method is illustrated in Fig. 3. An end plate 41 is positioned within the inner 25 cylinder near the inner end of the cathode 35. This end plate is supported by the cathode support member 20, and insulated therefrom. A potential is applied to the end plate by a connection extending from the tube through an insulating head to a battery 43. The polarity of 30 this potential is determined by the tube geometry and the extent of the magnetic field. It is to be adjusted for optimum operating conditions.

When the magnetic field is applied, and the 35 cathode energized, electrons are liberated from the cathode and, due to the force of the magnetic field, they rotate about the cathode and therefore approach the inner and outer anode electrodes alternately. The cut-away alternate 40 quarters of the inner cylinder expose the outer cylinder to the electrons. Since oppositely positioned anode electrodes are connected together, the device will generate oscillations in the manner of the oscillator of Fig. 1. The inner and outer cylinders, including the anode electrodes 45 13 and 15, constitute a resonant tank circuit. The anode connecting leads which become resonant have been eliminated, and therefore greater efficiency may be obtained at ultra high frequencies. A load circuit 33 may be connected 50 through suitable insulators to appropriate points on either side of the voltage node of the inner cylinder.

I claim as my invention:

1. An electronic device comprising an electron tube having an electron-emissive cathode, a resonant oscillatory circuit, and means for producing a magnetic field, said resonant oscillatory circuit comprising an inner and an outer cylinder concentrically positioned with respect to said cathode, said inner cylinder having an axially divided end portion the extensions of which form a pair of symmetrically positioned anode sections, and the portion of said outer cylinder adjacent the openings between said inner cylinder anode sections forming an intermediate pair of anode sections. 5

2. An electronic device comprising an electron 15 tube having an electron-emissive cathode, a resonant oscillatory circuit, and means for producing a magnetic field, said resonant oscillatory circuit comprising an inner and an outer cylinder separated by a distance small in comparison to their 20 diameter and concentrically positioned with respect to said cathode, said inner cylinder having an axially divided end portion the extensions of which form a pair of oppositely positioned anode sections, the portion of said outer cylinder adjacent the openings between said inner cylinder anode sections forming an intermediate pair of 25 anode sections. 25

3. An electronic device comprising an electron tube having an electron-emissive cathode, a resonant oscillatory circuit, and means for producing a magnetic field, said resonant oscillatory circuit comprising an inner and an outer cylinder separated by a distance small in comparison to their 30 diameter whose length is determined by the 35 oscillation frequency, concentrically positioned with respect to said cathode, said inner cylinder having a bifurcated end portion the extensions of which form two oppositely positioned anode sections, the portion of said outer cylinder adjacent the openings between said inner cylinder anode sections forming other anode sections. 40

4. A device of the character described in claim 3 in which said inner cylinder is electrically connected to and supported by said outer cylinder at 45 a radio frequency voltage node. 45

5. A device of the character of claim 3 which includes an end plate electrode within said inner cylinder.
